UNITED STATES PATENT OFFICE.

PHILIP H. ROBBINS, OF NEW YORK, N. Y., ASSIGNOR TO POIRETTE CORSETS, INC.,
OF NEW YORK, N. Y., A CORPORATION OF NEW YORK.

CORSET.

Application filed March 8, 1922. Serial No. 542,043.

To all whom it may concern:

Be it known that I, PHILIP H. ROBBINS, a citizen of the United States, residing at New York city, in the county of New York and State of New York, have invented certain new and useful Improvements in Corsets, of which the following is a specification.

This invention relates to an improvement 10 in corsets, the object being to provide a double restraining feature consisting of a front band of elastic being attached to the side edges of the back of the corset about two-thirds of the distance up from the bottom of 15 the corset, the remaining upper portion of the front elastic bands being connected by a comparatively broad elastic band extending across the back of the body of the corset and outside of the body portion. The upper 20 portion of the body portion of the corset which is disconnected from the front elastic bands mentioned has attached along the free edge thereof elastic sections adapted to be brought around the body within the body 25 of the corset, furnishing an additional reinforcing means.

It will be noted that this construction produces a corset with two independent circles at the upper part; the inner circle or 30 part of the corset is first adjusted to the body, after which its position is fixed, then the outer circle or part of the corset is secured in place affording an additional reinforcement. The comparatively broad 35 elastic band at the rear of the outer circle is capable of a slight vertical adjustment, according to the desires of the wearer, being held in the desired position by friction.

In the accompanying drawings:—

40 Figs. 1 and 2 are views in perspective showing the front and rear of the corset;

Fig. 3 is an enlarged fragmentary perspective view disclosing the manner in which the reinforcing bands are connected to the 45 upper part of the body portion of the corset;

Figs. 4 and 5 are modified views showing the re-arrangement of the elements included in the original structure forming a so-called "slip-on" corset;

Figs. 6 and 7 are modified views of still another form of corset where substantially the same elements are used, but are arranged in a different manner.

55 A, indicates the non-elastic body or back

portion of the corset, it preferably having stays 1, as indicated. The numerals 2 and 3 indicate elastic sections attached to the vertical edges of the non-elastic body or back portion A. These elastic portions 2 60 and 3 are preferably provided with front stays 4 being provided with eyes 5 for fastening the elastic sections together at the front, the lower portion of the stays 4 being provided with lacings 6.

As disclosed, the elastic sections 2 and 3 are secured to the back portion A about two-thirds the distance up from the bottom, the remaining upper portion of the elastic sections 2 and 3 being connected together by a comparatively broad elastic band 7 arranged on the outside of the back portion A. The upper free ends of the back A are in turn provided with elastic sections 8—8 attached to the edges thereof and adapted to extend 70 forwardly within the elastic sections 2 and 3. These sections 8—8 or inside bands are either provided with hooks and eyes 9 or lacings.

In applying this form of corset as disclosed in Figs. 1, 2 and 3, the elastic sections 8—8 are first brought together and fastened around the body after which the elastic sections 2 and 3 are brought around and secured at the front. The usual garter attachments 10 depend from the lower edge 80 of the garment.

Both the garment as a whole and its elastic band 7 may be made in any width or length with or without lacings in the back.

As shown in Figs. 4 and 5, the garment is disclosed in the form of the step-in variety of garment, the elastic sections 2 and 3 being made integral with non-elastic section B'. In this instance, however, the elastic band 7 is arranged at the front of the garment while an integral elastic band 8' is secured to the upper free end of the front section B instead of to rear section A as disclosed in the preferred form.

In the modified form shown in Figs. 6 and 7, the rear body portion A is normally separated and adapted to be connected by a suitable lacing. The broad elastic band 7 is likewise arranged at the front and made preferably in two sections provided with suitable fastening means for detachably securing them together, while the inner elastic sections 8—8 are secured to the upper 105 free end of the front section B. The elas-

tic sections 8—8 are connected together at the rear instead of the front, as described in the preferred form.

I claim,

- 5 1. A garment slit at the sides of the back part-way from the upper to the lower edge, an elastic band connected to the edges of the front and an elastic section or sections for connecting the edges of the back.
- 10 2. A garment having two broad elastic bands at the upper portion, one connecting the side edges of the back and the other the side edges of the front, the former band made in two parts and having fastenings at 15 the adjacent edges.
3. A garment comprising a non-elastic body portion, elastic sections secured to the edges thereof part-way from the upper to

the lower edges, an elastic band connected to the upper inner edges of the elastic sections 20 adapted to extend across and outside of the non-elastic body portion, and elastic sections secured to that portion of the non-elastic body portion not connected to the first-mentioned elastic sections.

25 4. A corset including alternate elastic and non-elastic panels, the outer panels slit part way from the upper edge, and elastic members secured to said slit edges and extending in opposite directions around the figure both 30 back and front, the alternate elastic and non-elastic panels forming two complete circles.

In testimony whereof I affix my signature.

PHILIP H. ROBBINS.
